United States Patent Office.

GEORGE H. POOL, OF NEW YORK, N. Y.

Letters Patent No. 60,782, dated January 1, 1867; antedated December 19, 1866.

IMPROVEMENT IN SPRING BEDS.

The Schedule referred to in these Letters Patent and making part of the same.

Be it known that I, GEORGE H. POOL, of New York, in the county of New York, and State of New York, have invented a new and useful "Improved Spring Bed;" and I do hereby declare that the following is a full, clear, and exact description of the construction and operation of the same, reference being had to the accompanying drawings, making a part of this specification, in which—

Figure 1 is a top view, the upper portion of the figure representing the bed with the slats in position, and the lower portion showing the same with the slats removed.

Figure 2 is a longitudinal vertical section.

Explanation of Figures.

a a', stout plank or joists constituting the head and foot of the framework. *b b'*, thin wooden sides of the framework. *c c'*, thin wooden slats, lying longitudinally. *d d'*, pliant wooden slats mortised into the plank *a*, at the head of the bed, slanting upward at an angle with the side of the plank *a*. *f f'*, slats similar to those lettered *d d'*, but longer and mortised into the plank *a'* at the foot of the bed. *g g g g*, elongated orifices in the pliant slats *d d' f f'*, near their upper extremities. *h h*, pins fastened at one end to the horizontal slats *c c'*, and passing through the orifices *g g g g*. *i i*, pins passing through the pins *h h*, beneath the slats *d d' f f'*, and securing them in position.

Construction and Operation.

The framework *a a' b b'* having been constructed, the thin wooden slats *d d'* are mortised into the stout head-plank *a*, making an angle with it, and in such a manner that the other extremities of the slats are on a level with the top of the framework. The slats *f f'*, similar to or longer by a few inches than those lettered *d d'* are in like manner mortised into the foot-plank *a'*, making the same or a greater angle with its side than *d d'*, made with *a*; the upper extremities of *f f'* being on the same level with those of *d d'*. The slats *c c'*, of similar width to *d d'* and *f f'*, are placed horizontally and longitudinally, resting on *d d'*, &c., and *f f'*, &c.; and held in position by the pegs or pins *h h*, which pass through the orifices *g g*, &c., while the pins *i i* prevent the pegs *h h* from being withdrawn from *g g*, &c., on the depression of either extremity of the slats *c c'*, and thus serve to keep the whole mechanism in position. The orifices *g g*, &c., are made of sufficient size to admit of free movement of the pegs *h h*, on the depression and elevation of the slats.

The great advantage of the "improved spring bed" consists in that, while the elasticity of the horizontal slats is added to that of the inclined slats, the whole of this elasticity is evenly distributed over the whole surface of the bed; for the slats *d d'*, at the head of the bed, being made shorter than those lettered *f f'*, at the foot of the bed, or being set at a more acute angle, or both, offer greater resistance to the superincumbent body just at the point where the weight is greatest, thereby maintaining the surface of the bed in level position.

The "improved spring bed" may be set up in its own framework, or may be adapted to any other kind of bedstead now in use.

Claim.

I claim as my invention, and desire to secure by Letters Patent—

The rails *c c'*, resting on the springs *d d'* and *f f'*, and attached thereto by means of the pins *h h* passing through the slots *g g*, said springs being made of greater or less elasticity by varying their length, or the angle at which they are inserted in *a* and *a'*, or by both of these means, as described and arranged.

GEORGE H. POOL.
